[57] CLAIM

The ornamental design for a calculator with advertising space for shopping cart handle, as shown and described.

DESCRIPTION

FIG. 1 is a top plan view of a calculator with advertising space for shopping cart handle, showing my new design;

FIG. 2 is a left side elevational view;

FIG. 3 is a right side elevational view;

FIG. 4 is a front elevational view;

FIG. 5 is a rear elevational view;

FIG. 6 is a bottom plan view;

FIG. 7 is a left side elevational view of a second embodiment of my new design;

FIG. 8 is a right side elevational view of the second embodiment;

FIG. 9 is a front elevational view of the second embodiment;

FIG. 10 is a rear elevational view of the second embodiment;

FIG. 11 is a bottom plan view of the second embodiment; and,

FIG. 12 is a perspective view of the embodiment of FIG. 1.

Fig. 1**Fig. 2****Fig. 3****Fig. 4**

Fig. 5**Fig. 6****Fig. 7****Fig. 8****Fig. 9**

Fig. 10**Fig. 11****Fig. 12**

UNITED STATES PATENT AND TRADEMARK OFFICE
CERTIFICATE OF CORRECTION

PATENT NO. : Des. 351,409
DATED : October 11, 1994
INVENTOR(S) : Charles H. Hood

It is certified that error appears in the above-identified patent and that said Letters Patent is hereby corrected as shown below:

In column 2, of the first page, in the line that begins "Fig.7" delete the word "elevational".

Signed and Sealed this

Twenty-sixth Day of December, 1995

Attest:

BRUCE LEHMAN
